US0D1033022S

(12) **United States Design Patent** (10) Patent No.: **US D1,033,022 S**
(45) Date of Patent: ** Jul. 2, 2024

(54) **SHOE**

- (71) Applicant: **Reebok International Limited**, Altrincham (GB)
- (72) Inventors: **Matthew Boudreau**, North Attleboro, MA (US); **Matthew Costa**, Mattapoisett, MA (US); **Dennis Gaboriault**, Millbury, MA (US)
- (73) Assignee: **Reebok International Limited**, Altrincham (GB)
- (**) Term: **15 Years**
- (21) Appl. No.: **29/805,969**
- (22) Filed: **Aug. 31, 2021**

Related U.S. Application Data

- (63) Continuation of application No. 29/702,552, filed on Aug. 20, 2019, now Pat. No. Des. 931,582, which is a continuation of application No. 29/646,475, filed on May 4, 2018, now Pat. No. Des. 862,854.

CLAIM

The ornamental design for a shoe, as shown and described.

DESCRIPTION

FIG. 1 is a bottom front perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the shoe that form no part of the claimed design.
